UNITED STATES PATENT OFFICE.

JOHN O. ALMEN, OF SEATTLE, WASHINGTON.

INTERNAL-COMBUSTION ENGINE.

1,300,098.

Specification of Letters Patent.

Patented Apr. 8, 1919.

Application filed March 6, 1917. Serial No. 152,484.

To all whom it may concern:

Be it known that I, JOHN O. ALMEN, a citizen of the United States, residing at Seattle, in the county of King and State of Washington, have invented certain new and useful Improvements in Internal-Combustion Engines, of which the following is a specification.

This invention relates to internal combustion engines and, more particularly, to improvements in the engine illustrated and described in patent application Serial No. 114,982, filed by me August 15, 1916.

The primary object of the invention is to produce an engine of this class which will be of light weight, compact form, efficient in consumption of fuel, and will operate with a small amount of vibration.

A further object is the provision of an improved construction of valves and the operating mechanism therefor which will afford a better control over the admission of the explosive mixture, and regulate the exhaust so as to obviate back pressure.

25 A further object is the provision in an engine of this class of improved friction-reducing appliances.

A still further object is the provision of packing devices to render the engine inlet and exhaust connections leak-proof with an absence of friction.

Because of the above-mentioned characteristics which are attained by my invention, it is peculiarly adapted to aeroplanes, automobile, marine and other applications. An engine embodying my invention is illustrated in the accompanying drawings, in which—

Figure 1 is a vertical longitudinal section. Fig. 2 is an end elevation of the same shown broken away and partly in section, said section being taken substantially through 2—2 of Fig. 1. Fig. 3 is a detail sectional view through 3—3 of Fig. 1. Fig.

45 Fig. 4 is a detached plan view of one of the expansible packing rings employed in the engine. Fig. 5 is a sectional view taken diametrically through Fig. 4. Fig. 6 is a vertical section through 6—6 of Fig. 1. Fig.

50 Fig. 7 is an end elevation of one of the valve members shown detached. Fig. 8 is a side elevation of the same. Fig. 9 is a face view showing somewhat diagrammatically a packing ring, controlling plates therefor, the plate-spacing bars, and illustrating the preferred form of port for each cylinder.

As best shown in Fig. 1, the engine is provided with a casing comprised of a section 10 interposed between two cylinder sections 11 and having secured to the outer ends of the latter head members 12. Extending axially through such case and journaled in bearings 14 provided, preferably, in said head members, is the engine shaft 15.

The casing sections 11 are formed with a plurality of bores 16 constituting the cylinders, as they will be hereinafter designated. In the present embodiment seven cylinders are shown in each of the sections 11. These cylinders are arranged concentrically with respect to the axis of the shaft 15, those in one of the members 11 being complementary to and in axial alinement with those of the other cylinder member. Said cylinders open from their inner ends into the chamber 13 within the central section 10, and adjacent to their outer ends are provided radially disposed passages 17 which serve alternately for intake and exhaust purposes.

Adjacent to their inner ends the cylinders are provided with one or more complementary exhaust ports 18, shown in Figs. 1 and 4. Operable within the respective cylinders are pistons 19 which are made relatively long to furnish large bearing surfaces with respect to the cylinders and also to keep the ports 18 closed with respect to the chamber 13. Said pistons are also provided at their outer ends with peripherally spaced extensions 21 which serve, upon occasion, as valve elements with respect to the supplementary exhaust ports 18. Each pair of axially alined pistons is rigidly coupled by a piston rod 20 having a central globular portion 22 from which extends a disk element 23 arranged in rectangular relation to the axis of the respective rod and having conical shaped end surfaces 24 and 24¹, whose apices, if produced, will be located at the center of the globular part 22.

About the outer portion of a surface 24, each of the disks is provided with gear teeth 25 which are successively engaged by the teeth 26 of an annular wobbling collar 27 having tapering internal and external conical surfaces 28 and 29. At the opposite side of a disk element 23 from the wobbling collar 27 is a second wobbling collar 27¹ similar to the first-named one by having corresponding internal and external conical surfaces 28¹ and 29¹, but is unprovided with gear teeth.

Each such assembly of a disk and a pair of collars is contained in an annular casing formed of two complementary parts 30 (Fig. 1), the same being provided with an interior 5 globular surface which fits against the outer peripheral surfaces of the respective disk element 22 and the associated collars 27 and 27¹; the annular casings 30 having openings 32 to accommodate the piston rods 20 and 10 about the edge of each such opening is a circular ridge 33 whose office is to receive thrusts imparted through the collars and said disks to the casings which, in turn, afford wabbling motion to a wabbler frame W 15 operable within the chamber 13.

For convenience in manufacture, the frame W is desirably composed of a plurality of inter-fitting annular elements 34, 34¹ and 34². The elements 34² are formed 20 with a plurality of openings such as 35 (Fig. 2) with a communicating peripheral recess 35¹ (Fig. 1) for each, to respectively accommodate a casing 30 and a circumferential flange 30². Within each such recess is also 25 provided a ring 36 fixedly secured to and forming in effect, a part of the wabbler frame.

The diameters of said flanges are somewhat less than the diameter of a recess 35¹ 30 thereby allowing the casings 30 limited amounts of orbital movements. These casings are, however, secured against rotating by the provision of peripherally disposed 35 cavities 38 in said flanges to receive protuberances 39 provided on the non-rotatable rings 36.

40 represents anti-friction balls interposed between the wabbling frame W and a peripherally grooved bushing 41 provided on 40 a journal 42 having its axis arranged obliquely with respect to the axis of the shaft. The journal 42 forms part of a sleeve 42¹ which is seated on a tubular support 43 surrounding the shaft. Said support is held 45 concentrically about the latter by means of ball-bearings 44 holding the ends of the support concentrically within wheels 45 whose hubs 45¹ are rigidly secured, as by keys 46, to the shaft.

50 Between an inner wall 11¹ of the cylinder sections and the exterior of wheels 45 I provide ball-bearings 47 which serve to prevent any lateral deflection of the shaft. The wheels 45 are also provided with series of gear-teeth 48 and 48¹ which are 55 respectively engaged by series of gear-teeth 49 and 49¹ provided on opposite sides of the wabbling frame W. The teeth of the frame series, however, exceed in number 60 those of the respective wheel series, whereby the wabbling of the frame will effect the rotation of the wheels to correspondingly drive the shaft. The wheels are furthermore provided with annular surfaces 50 65 which have rolling contact with annular sur-

faces 51 provided on the wabbling frame to relieve the gear teeth from excessive friction or end-thrusts due to the wabbling action of the frame W and corresponding in function to the rolling surfaces 24 and 24¹ 70 with respect to the opposing surfaces 29 and 29¹ of the several thrust collars 27 and 27¹.

Provided in the cylindrical chambers 52 in each end of the engine casing, and communicating with the respective passages 17, 75 is a rotary valve 53 which is secured to the shaft by a key 54. Each valve is formed with a body having two concentrically arranged walls 55 and 56 to provide annular compartments 57 and 58 about a valve hub 80 53¹ and intermediate the above-named walls.

Intake and exhaust ports 59 and 60 are provided in the valve, the former extending through conduits 59¹ into the compartment 57 to which the explosive mixture is supplied from a manifold compartment 57¹ in a head 12 by a pipe 61, and the other ports 60 open into the compartment 58. Within the latter I provide an annulus 62, shown detached in Figs. 7 and 8, provided with conduits 63, one for each of the ports 60 and fitting against the inner peripheral surface 56¹ of the valve wall 56 and affording communication between such ports and an outlet 64 provided in the adjacent head 12. 95

The conduits 63 are integrally connected with each other by tie elements 65 in each of which is included a loop 65¹ which may contract or expand when subjected to varying degrees of temperature from the hot 100 exhaust gases, and still maintain the conduits in juxtaposition with the wall surface 56¹.

Within the compartment 57 and fitted against the inner peripheral surface 55² of 105 wall 55 is a cut-off valve 66 having a plurality of ports 66¹ which may be brought into full partial register with the conduits 59¹ when the ports 59 of the latter are in register with cylinder passages 17. The 110 adjustment of a cut-off valve is effected by means of a spur-pinion 67 engaging a number of teeth such as 68 (Fig. 1) provided in the respective cut-off valve to suitably rotate the cut-off valve with respect to the passages 17. As shown, a pinion 67 is actuated by a rod 67¹ through the medium of a crank-arm 67². A valve 53 is machined to be of less diameter than the chamber 52 in which it operates, thereby affording an annular 115 space for packing devices which insure a non-leakable connection between the various cylinder passages 17 and the respective valve. These packing devices each comprise an arcuate plate 69 whose concave surface is fitted to the outer peripheral surface of the valve wall 56 and held against revolving with the valve by resilient stop means such as spring elements or flexible bars 70, Fig. 9, whose ends extend into holes 70¹ 120 125 130

provided in the casing, as indicated in Fig. 1.

Each of said plates is provided with a conical aperture 71 of circular shape corresponding to opposing conical mouths 17¹ provided for the respective passages 17. To prevent leakage between the cylinder-casing sections 11 and the plates 69, I provide pairs of expandable rings (shown detached 10 in Figs. 4 and 5) which also serve to hold said plates in contact with valve walls 56. More particularly, each pair of such rings comprises an outer ring 72 having external faces 72¹ which taper in both directions from 15 a circumferential apex 72² to fit into the respective said plate opening and the passage. The inner ring 73 is likewise provided with external tapering faces 73¹ to fit against angularly arranged faces 72² of 20 a groove provided interiorly of the outer ring. The outer and inner rings are respectively cut obliquely, as indicated by lines 74 and 75, so that the resiliency of the material of which the rings are formed will 25 cause them to expand.

76 indicate screw-threaded holes extending through casing into the cylinders for the reception of sparking plugs, not shown, of any usual or suitable ignition system.

30 In operation, the explosive mixture is supplied by pipes 61 to the intake manifolds 57¹ at opposite ends of the engine casing and, subject to the control of the shaft driven valves 53 and the supplementary cut-off valves 66, is delivered into the various cylinders 16 through the respective passages 17, which latter also serve, subject to the valves 53, to carry away the major portion of the exhaust gases.

40 After the manner of four-cycle engines, the charges are drawn into each cylinder during the suction strokes of the pistons, compressed during the following reverse strokes, then exploded in the third strokes 45 to impel the pistons which, in the fourth strokes, effect the discharge of the spent gases.

The reciprocating of the pistons acts through the medium of piston-rod disks 23 and casings 30, to afford wobbling motion to the frame W because of its being mounted on a journal 42 whose axis is oblique to the axis of the engine. The casings 30 and the flange elements 30² thereof being of less 55 diameters than the openings 35 and recess 35¹, respectively, of the casings, afford movements of such casings to compensate for the wobbling movements of the wobbler frame W.

60 As the frame W wobbles, the annular faces 51 thereof track against the opposing faces 50 of wheels 45, while the gear teeth 49 and 49¹ of the wobbler engage the wheel teeth 48 and 48¹. By reason of there being 65 a greater number of teeth on the wobbler

than on said wheels, the wheels are caused to rotate at a slower speed to similarly drive the shaft which is keyed thereto.

By the provision of series of gear teeth 25 on the piston rod disks 23 engaging series 70 of teeth 26 on the collars 27, and due to the different number of teeth in the respective series, rotary motion is imparted to the piston rods to cause the associated pistons to rotate for the purpose of revolving piston 75 extensions 21 to time the opening and closing of the supplementary exhaust ports 18.

The above-described mechanisms for rotating the pistons influence the same to cause ports 18 to be open at the termination of 80 the explosion strokes of the respective piston, and acting in co-operation with the exhaust passages 68, afford a quick and effective exhaust of the gaseous products of combustion from the cylinders prior to the intake strokes of the pistons.

What I claim, is—

1. An internal combustion engine comprising a plurality of circularly arranged cylinders each having a passage, a cylindrical rotary valve having exhaust and inlet compartments respectively, provided with passageways that communicate in the travel of the valve with the passages to the cylinders, a normally stationary cylindrical cut off member within said valve having openings that register with the inlet passageways in said valve, and means for adjusting the position of said cut off member to vary the cut off of said valve. 90

2. An internal combustion engine comprising a shaft, a plurality of circularly arranged cylinders around said shaft each of said cylinders having an inwardly directed passageway, means for establishing a driving connection between said cylinders and said shaft, a valve having exhaust and inlet compartments respectively provided with openings that are caused by the travel of the valve to register with the passageways to said cylinders, and a normally stationary adjustable cut off member disposed within said valve and having passageways that register with the inlet openings in said valve and afford a variable cut off for 110 explosive mixture.

3. An internal combustion engine comprising a plurality of circularly arranged cylinders each having a passage, a cylindrical valve having an inner annular compartment for explosive mixture and an outer annular compartment for exhaust gases each of said compartments having passageways that are caused to register with the passages to the cylinders by the rotation of the 120 valve, a stationary cut off member disposed within said inner annular compartment and having openings that are caused to register with the inlet openings in said valve, and means for adjusting the position of said cut 130

off member to vary the cut off for explosive mixture.

4. An engine of the class described comprising a plurality of circularly arranged cylinders each having a passage, a rotary valve having ports that are caused to register with said passages by the rotation of said valve, a plate interposed between each of said cylinders and the valve, automatically acting packing members between said plates and said cylinders and adapted to expand under pressure to prevent leakage, and flexible stops associated with said cylinders to prevent displacement of said plates.

5. An engine of the class described comprising a plurality of cylinders each having a passage that terminates in cone shaped mouth portion, a rotary valve having ports that register with said passages in the travel of the valve, a plate interposed between each of said cylinders and said valve each of said plates having a passageway that has its outer edge beveled off to form a cone shaped mouth disposed opposite the cone shaped mouth of a cylinder passageway, expandible packing rings disposed within the recess formed by said two cone shaped mouths and means coöperating with said packing rings to prevent displacement of said plates.

6. The combination with an engine cylinder having a port provided with a conically recessed mouth of a valve controlling the inlet and exhaust to said cylinder, a plate interposed between said valve and said cylinder and having a conical passage disposed opposite the conical mouth of said port and an expandible packing device disposed within the recesses between said port and said plate comprising an outer split ring having coniform exterior and interior surfaces and an inner split ring having a coniform external surface and disposed within said outer split ring the split portions of said rings being offset with respect to each other.

7. An engine having a plurality of cylinders arranged in parallel relations and provided with conical ports, a cylindrical

rotary valve having ports therein, a plate interposed between each of said cylinders and the valve and provided with a conical port, and expansion rings constituting wedges positioned in said conical ports, and flexible stops coöperating with said rings to prevent the displacement of said plates.

8. An internal combustion engine including a rotary cylindrical valve having an outer annular compartment and an inner annular compartment and a separable member disposed within said outer compartment to afford a conduit for exhaust gases and adapted to expand and contract independently of the valve in response to variations in temperature.

9. An internal combustion engine comprising a plurality of circularly arranged cylinders, a cylindrical rotary valve coöperating with said cylinders said valve having an inner annular compartment for explosive gases and an outer annular compartment that connects with said cylinders and a separable member disposed within said outer compartment and provided with conduits for the escape of exhaust gases and flexible sections connecting said conduits to permit said member to expand independently of said valve due to the heat of the exhaust gases.

10. An internal combustion engine having a plurality of cylinders, a rotary valve having passages therethrough for the supply of an explosive mixture to the engine cylinders, and a circular member carried in the valve, said member being provided with spaced conduits for the escape of exhaust gases from the various cylinders and having yielding portions intermediate the adjacent conduits to compensate for contraction or expansion of said member due to variations of temperatures when uninfluenced by or subjected to the heat of exhaust gases.

Signed at Seattle, Washington, this 20th day of February, 1917.

JOHN O. ALMEN.
